BY

Louis Hecke ATTORNEY

UNITED STATES PATENT OFFICE.

JOSEPH LEDERER, OF NEW YORK, N. Y.

DESIGN FOR AN INVERTED GAS-BURNER.

No. 38,748.

Specification for Design.

Patented Aug. 13, 1907.

Application filed July 3, 1907. Serial No. 382,116. Term of patent 7 years.

To all whom it may concern:

Be it known that I, JOSEPH LEDERER, residing in the city, county, and State of New York, have invented a new, original, and ornamental Design for Inverted Gas-Burners, of which the following is a specification, reference being had to the accompanying drawing, forming part thereof.

The figure is a view in elevation of an inverted gas-burner showing my new design.

I claim;—

The ornamental design for an inverted gas-burner, as shown.

JOSEPH LEDERER.
